UNITED STATES PATENT OFFICE.

FREDERICK A. FRERICHS, OF PHILADELPHIA, PENNSYLVANIA, ASSIGNOR TO THE HORN & BRANNEN MANUFACTURING CO. INC., OF PHILADELPHIA, PENNSYLVANIA, A CORPORATION OF PENNSYLVANIA.

DESIGN FOR A LIGHTING-FIXTURE UNIT.

Application filed September 27, 1924. Serial No. 10,909. Term of patent 7 years.

To all whom it may concern:

Be it known that I, FREDERICK A. FRERICHS, a citizen of the United States, residing at Philadelphia, in the county of Philadelphia and State of Pennsylvania, have invented a new, original, and ornamental Design for Lighting-Fixture Unit, of which the following is a specification, reference be-

ing had to the accompanying drawing, forming part thereof.

The figure is a front elevation showing my new design.

I claim:

The ornamental design for a lighting fixture unit, as shown.

FREDERICK A. FRERICHS.
